ATTORNEYS—

UNITED STATES PATENT OFFICE.

ROBERT O. BINGHAM, OF SIDNEY, OHIO, ASSIGNOR TO THE WAGNER MANUFACTURING COMPANY, OF SIDNEY, OHIO, A CORPORATION OF OHIO.

GRIDDLE.

1,201,138.

Specification of Letters Patent.

Patented Oct. 10, 1916.

Application filed May 12, 1915. Serial No. 27,537.

To all whom it may concern:

Be it known that I, ROBERT O. BINGHAM, a citizen of the United States, and a resident of Sidney, county of Shelby, and State of Ohio, have invented a new and useful Improvement in Griddles, of which the following is a specification, the principle of the invention being herein explained and the best mode in which I have contemplated applying that principle, so as to distinguish it from other inventions.

The present improved cooking utensil or griddle, designed primarily for baking cakes, has the usual smooth top surface with this object in view, the improvements residing principally in the construction of the under surface and of the lateral edge of the griddle, whereby a uniform distribution of heat to all portions of such surface is secured, by creating a proper circulation of the heated gases which ordinarily constitute the heating medium. Particularly where a gas or oil burner is used as the source of heat, a slight draft or current of air will 20 tend to disturb the flame sufficiently to prevent proper heating of the cooking surface of the utensil, and the construction of the latter has accordingly been designed with particular reference to meeting this and 25 similar conditions.

To the accomplishment of the foregoing and related ends, the invention, then, consists of means hereinafter described and particularly pointed out in the claim.

55 In said annexed drawing: Figure 1 is a top perspective view of my improved utensil; Fig. 2 is a bottom perspective view of the same, and Fig. 3 is a central vertical section thereof taken on the plane indicated by the line 3—3, Fig. 2.

The utensil, which may be constructed of aluminum or any other suitable metal or material, comprises essentially a flat plate 1, the upper smooth face of which constitutes the cooking or baking surface, when such plate is located over a suitable source of heat. Laterally projecting from the plate at a suitable angle is a handle 2 of usual form and construction attached to such plate in any suitable way.

The plate is formed with a shallow upturned rim 3, about its periphery, which merges into a down-turned flange 4 of appreciable depth, likewise extending about the 55 entire periphery. This flange is inclined

outwardly to the plane of the plate (see Fig. 3), so as to have a larger diameter at its lower than at its upper edge, and is furthermore provided with a series of elongated apertures 5 uniformly distributed throughout its length save at the point of attachment of the handle 2 to the plate, as shown in Fig. 2.

The under side of the plate is provided with a plurality of spiral ribs 6, radiating from a central point 7 on such bottom, to the flange 4 with which the outer ends of the ribs merge. Such ribs, together with the flange, it will accordingly be seen, define a series of spaces 8 having the form of spiral sectors, one or more of the apertures 5 in the flange opening into each such space. Thus, save for the two spaces adjoining the point of attachment of the handle, two apertures open into each one, as shown in Fig. 2. It will be understood that the lower edges of the ribs 6 and flange 4 lie in substantially the same plane and that such plane is parallel with plate 1.

As a result of the foregoing construction and particularly of the sub-division of the circular space, laterally inclosed by the flange, by means of the spiral ribs, it will be observed that the heated gases, if they strike the bottom of the plate at all centrally, will be diverted in radiating directions from such center. Such diversion is not only produced by the ribs, but is facilitated by the sloping conformation of the flange, so that the apertures therein which communicate with the spaces between such ribs, respectively, constitute, in effect, draft openings through which the heated gases can rise upwardly. This same form of flange brings the gases, as they finally pass away from the utensil, into close proximity to the cooking surface all around its edge, and thus insures the thorough and complete heating of such surface throughout its entire extent. Only a very considerable current of air such as will not ordinarily be encountered, will affect this action of the ribs in properly diverting and distributing the flow of heated gases striking the under side of the utensil.

The spiral ribs, in addition to serving the important function above described, of course give additional strength to the bottom of the plate and prevent warping of the latter. Such ribs being flush with the flange, come in contact with any plane, level sur-

face, and thus not only assist in supporting the utensil on the top of an ordinary stove, but are also adapted to contact with a surface of the kind usually found in electric heaters, and thus adapt the utensil for use with the latter as well as with a gas, gaso-
lene, oil, wood or coal stove.

Other modes of applying the principle of my invention may be employed instead of 10 the one explained, change being made as regards the mechanism herein disclosed, provided the means stated by the following claim or the equivalent of such stated means be employed.

15 I therefore particularly point out and distinctly claim as my invention:—

An appliance of the character described, comprising an approximately circular alu-

minum plate having a smooth surface; an upturned rim peripherally bounding such surface; a downturned peripheral flange provided with aligned apertures spaced approximately along the center line of said flange, said flange sloping downwardly, forming with said plate a chamber for receiving the heated gases; and a comparatively large number of spiral ribs on the under surface of said plate, said ribs radiating from a substantially central point and merging at their outer ends with said flange so as to define sectorlike spaces, each such space communicating with one or more of the apertures in said flange substantially as described and shown.

Signed by me, this 10 day of May, 1915.

ROBERT O. BINGHAM.
